(57) **CLAIM**

The ornamental design for a rotary grater, as shown and described.

DESCRIPTION

FIG. 1 is a side perspective view of a rotary grater showing an exemplary embodiment of our new design;

FIG. 2 is a front view of the rotary grater of FIG. 1;

FIG. 3 is a back view of the rotary grater of FIG. 1;

FIG. 4 is a side view of the rotary grater of FIG. 1;

FIG. 5 is a side view of the rotary grater of FIG. 1;

FIG. 6 is a top view of the rotary grater of FIG. 1; and,

FIG. 7 is a bottom view of the rotary grater of FIG. 1.

The broken lines are for illustrative purposes only and form no part of the claimed design.
